ARTHUR W. SAVAGE
By Milton E. Robinson

ATTORNEY.

UNITED STATES PATENT OFFICE.

ARTHUR W. SAVAGE, OF UTICA, NEW YORK, ASSIGNOR, BY MESNE ASSIGNMENTS, TO THE SAVAGE ARMS COMPANY, OF SAME PLACE.

FIREARM.

SPECIFICATION forming part of Letters Patent No. 634,034, dated October 3, 1899.

Application filed April 21, 1897. Serial No. 633,123. (No model.)

To all whom it may concern:

Be it known that I, ARTHUR W. SAVAGE, of Utica, in the county of Oneida and State of New York, have invented certain new and useful Improvements in Firearms; and I do hereby declare that the following is a full, clear, and exact description of the invention, which will enable others skilled in the art to which it appertains to make and use the same, reference being had to the accompanying drawings, and to the letters and figures of reference marked thereon, which form part of this specification.

The main object of my present invention is to provide a hammer-indicator for a hammerless firearm, which indicator has sundry advantages in operation and construction, as hereinafter more particularly set out, and hammer-operating mechanism, also hereinafter set forth.

Figure 1 shows a longitudinal section of the mechanical parts of a magazine-firearm embodying my present improvements with the parts in open position. Fig. 2 shows a partial longitudinal section showing the breech-bolt closed and the firing-pin or hammer cocked. Fig. 3 shows the same as Fig. 2 after the trigger has been pulled and the firing-pin or hammer is operated. Fig. 4 shows a partial section 30 in connection with a portion of the frame, showing the hammer retracted by the retractor. Fig. 5 shows a top or plan view of a portion of the breech-bolt. Fig. 6 shows a perspective view of the front end or tip of the hammer or firing-pin. Fig. 7 shows a retractor and its spring removed from the other parts and on a side elevation. Fig. 8 shows a plan view of the same.

Referring to the reference letters and figures in a more particular description of the device, 1 indicates the barrel; 2, the fore-stock; 3, the butt-stock, and 4 the frame. The butt-stock is secured to the frame by the screw 5 entering the rear end of the lower tang of the frame. The breech-bolt 6 is provided with a wing-like projection 6^a, having a cam-groove, the position and form of which are shown in dotted lines at 6^b in Figs. 2 and 3, and is operated by a finger-lever 7, pivoted to the frame 50 at 8 and having a curved arm 7^a, which en-

gages with the wing portion of the breech-bolt by a stud on the end of the arm 7^a, which is received in the cam-groove. The breech-bolt 6 receives in a cylindrical opening in its body the hammer or firing-pin, consisting of 55 a spindle or shaft 9 and a head 9^a, having a point or tip 9^b, adapted to be projected through an aperture in the front end of the breech-bolt and strike the cartridge-primer. The rear end of the hammer is provided with 60 a hook or L-shaped extension 9^c, which is adapted to engage with the sear 10. The firing-pin or hammer is secured in the breech-bolt by a bushing 11 at the rear end of the breech-bolt, and on the spindle of the firing-pin are provided a coiled spring 12 and a washer 13. The head of the firing-pin is provided with a shoulder *a*, adapted to engage with the downwardly-extending projection of the indicator 14 when the hammer or firing- 70 pin is cocked and in the position shown in Fig. 2. The indicator 14 is received in a recess in the top of the breech-bolt and is secured by a cross-pin 15, on which it is pivoted, so as to have a limited swinging movement. 75 The washer 13 is also adapted to engage with the downwardly-extending projection 14^a of the indicator 14. The sear 10 is pivoted on a cross-pin 16, extending transversely across the frame of the gun, and is operated by a 80 trigger 17, pivoted in the frame at 18 and acted upon by a trigger-spring 19, secured to the lower tang of the frame at 20.

On the wing portion of the breech-bolt is pivoted at 21 the retractor 22, which is forked 85 at its front end to adapt it to engage on the cross-pin 16 in the frame and is extended at its rear end to adapt it to engage with the hooked portion 9^c of the hammer or firing-pin, or, more particularly, the rear end of the retractor engages on the cam *b*, formed in the front side of this firing-pin extension at certain times and at other times in the rounded notch *c*, formed in the lower end of this same firing-pin extension. The U-shaped spring 95 23 is secured to the retractor by having its bent end engaged in a notch in the upper side, and this spring operates the retractor by engaging on the under side of the breech-bolt. 100 Cartridges in the magazine are indicated

by A; but as the magazine mechanism is not involved in the present improvements detailed description and illustration are omitted.

The operation of the device as to the firing-pin indicator is as follows: When the breech-bolt is closed from the position shown in Fig. 1 (where the body of the breech-bolt lies immediately under the upper tang 4^a of the frame) toward the position as shown in Figs. 2 and 3, the hooked position 9^c of the firing-pin or hammer is caught by the shoulder 10^a on the sear, the sear being held in position to engage it by reason of the spring 19 operating on the trigger 17. The firing-pin is thus held back while the forward and breeching-up movement of the breech-bolt is completed and the spring is compressed between the head 9^a and washer 13 on the front end of the firing-pin and a bushing 11 at the rear end of the breech-bolt. When this movement is completed, the parts are in the position shown in Fig. 2. When the hammer is drawn back with reference to the breech-bolt in the movement which is described, the shoulder a on the front end of the hammer engages with the projection 14^a of the indicator and causes it to swing on its pivot into the position shown in Fig. 2, where its rear end projects above the general surface of the top of the breech-bolt, where it can be readily observed or felt. When the trigger is pulled and the sear releases the firing-pin or hammer, it is projected forward by the operation of the spring 12, and the point or tip 9^b strikes the primer and explodes the cartridge at the same time the washer 13 engages with the projection 14^a and forces the indicator into the closed position shown in Fig. 3. The washer 13 fits loosely on the spindle of the hammer or firing-pin, as will be noted by an examination of the drawings, and in case the firing-pin is not held back, either by the primer or something else, so as to take its complete forward position, as the same is shown in Fig. 3, the washer 13 will be held back slightly at its upper side by the projection on the indicator, while the lower side of the washer may follow the head of the firing-pin. In case the firing-pin is held back or after its blow is forced back in a slight degree by the primer or from any other cause the washer 13 will still engage with the projection of the indicator and hold it in closed position.

In order to enable the firing-pin to be removed without removing the indicator 14, the front end of the head 9^a is flattened, as shown at d, so that when the bushing 11 is unfastened and the firing-pin, with its spring and head, is drawn back until the shoulder a strikes on the indicator projection it may then be given a partial rotation to bring the flat portion d on the upper side, when the firing-pin may be completely withdrawn, the flat portion d affording no point of engagement with the projection on the indicator. The firing-pin may be replaced by performing operations in the reverse order.

The object of the retractor 22 is to withdraw the point 9^b of the firing-pin from projecting at the front end of the breech-bolt after the firing-pin has operated and so as not to interfere with the movement of the cartridges from the magazine or in loading the gun and so as to avoid any danger of premature explosion by reason of the firing-pin engaging with the primer of a loaded cartridge.

Starting with the parts in the position in which they are shown in Fig. 3, immediately after the shot has been discharged the first movement of the breech-bolt is downward to disengage the shoulder S on the rear of the breech-bolt from the shoulder S' on the frame. In making this movement the retractor 22 is rocked from the position shown in Fig. 3 to the position shown in Fig. 4 by reason of the forked end of the retractor engaging with the cross-pin 16, which is stationary. As the retractor 22 makes this movement the rear end operates on the cam b, retracting the firing-pin slightly from the position shown in Fig. 3 to that shown in Fig. 4, and the retractor finally comes to rest, with the end engaging in the notch c. The breech-bolt then completes its movement, sliding under the upper tang 4^a of the frame, as illustrated in Fig. 1. As the breech-bolt is closed again just before the completion of its movement the forked end of the retractor 22, then being in the position shown in Fig. 4, engages with the cross-pin 16, and as the rear end of the breech-bolt finally rises in completing its movement and the retractor is swung from the position shown in Fig. 4 to that shown in Fig. 2, where it is out of the way of the firing-pin when the trigger is pulled. It will be noted that in the closing movement of the breech-bolt there is an interval of time when the rear end of the retractor is not engaged with the notch c in the end of the hammer and when the forked end is not engaged with the cross-pin 16. The main office of the spring 23 is to prevent at such time the front or forked end of the retractor (which is heavier than the rear end) from dropping down into a position to not engage with the cross-pin. At other times than during such interval the retractor is held either by the cross-pin 16 or the notch c. The spring 23 is also useful in causing the retractor 22 to assume its proper position when the parts are being assembled and the bolt is withdrawn from the frame.

A friction device which would prevent the accidental movement of the retractor 22, except when it is moved in the opening or closing of the bolt by reason of the forked end engaging with the cross-pin 16, would answer substantially all the useful purposes of the spring 23.

If through any defect of parts or rusting or binding the indicator 14 fails to operate and close when the gun is fired, the same will be rubbed down and forced into the closed position as it passes under the shoulder S' and the tang 4^a. The indicator 14 is prevented from

opening too far by reason of the front end engaging with the breech-bolt at the front end of the recess which contains the indicator, as shown particularly in Fig. 2, Fig. 3 showing the slight clearance which allows the necessary swinging movement of the indicator. The rear end of the indicator is preferably made on an incline, affording a shoulder which will limit its movement in closing.

10 What I claim as new, and desire to secure by Letters Patent, is—

1. The combination with a breech-bolt, of a firing-pin or hammer mounted therein, and having a fixed shoulder and a yielding shoulder, of a pivoted indicator received in a recess in the side of the bolt, and having a portion in the path of movement of the shoulders on the firing-pin, and a portion arranged to be projected beyond the face of the bolt, substantially as set forth.

2. The combination of a reciprocating breech-bolt and firing-pin received in a recess therein, and having a fixed shoulder *a*, a ring 13 mounted on the firing-pin, a spring 12 and an indicator 14 received in a recess in the side of the bolt, and having a portion engaging with the shoulder *a* and ring 13, and a portion adapted to be projected beyond the side of the bolt, substantially as set forth.

3. The combination in a firearm, of the breech-bolt constructed and arranged to drop at its rear end and retire, a hammer or firing-pin carried by the breech-bolt, a hammer-retractor pivoted on the breech-bolt at its rear end and arranged to operate on the hammer and a fixed portion of the firearm with which the retractor engages whereby the retractor is operated, substantially as set forth.

4. The combination with a firearm, of a breech-bolt, a firing-pin and retractor pivoted on the breech-bolt and operating on the firing-pin, and having a fork and a fixed portion of the said firearm with which said fork engages, substantially as set forth.

45 5. The combination with a firearm having a fixed part, of a breech-bolt arranged to drop at its rear end and retire, a firing-pin or hammer mounted in the breech-bolt and having a cam-surface thereon, a retractor pivoted in the breech-bolt and having a portion engaging with the cam-surface on the hammer, and a portion detachably engaging with the fixed part of the firearm, substantially as set forth.

60 6. The combination with a firearm having a fixed part, of a breech-bolt arranged to drop at its rear end and retire, of a firing-pin or hammer mounted in the bolt, a hammer-retractor mounted in the bolt and engaging with the hammer, and detachably engaging with a fixed portion of the firearm whereby the re-

tractor is operated by the dropping of the rear end of the bolt, substantially as set forth.

7. The combination with a firearm, of a breech-bolt arranged to drop at its rear end and retire, a hammer mounted in the breech-bolt, and having a cam-surface *b*, a notch *c*, and a retractor 22, pivoted substantially at its middle on the breech-bolt, and having a portion engaging with the cam-surface *b*, a fixed pin in the frame, and a forked portion 7c engaging with said fixed pin, substantially as set forth.

8. The combination of a breech-bolt having a firing-pin recess, an indicator projecting in the said recess, a firing-pin having shoulders 75 arranged to engage the indicator and moving it both ways, substantially as set forth.

9. The combination of a breech-bolt having a firing-pin recess, an indicator projecting into said recess, a reciprocating firing-pin or hammer having a shoulder for engaging and operating the indicator and cut away permitting the firing-pin or hammer to be turned to disengage the shoulder and permit the firing-pin to be removed, substantially as set forth. 85

10. The combination of a breech-bolt having a firing-pin recess and an indicator-recess communicating with the firing-pin recess, an indicator projecting into the firing-pin recess, and a firing-pin or hammer operating along its 90 recess across the intercommunicating opening between the two recesses, and not leaving it in either direction, and engaging with the indicator, substantially as set forth.

11. The combination of a breech-bolt having a firing-pin recess, an indicator-recess communicating with the firing-pin recess, an indicator projecting into the firing-pin recess and the reciprocating firing-pin or hammer arranged at said intercommunicating opening, and of a length so as not to leave it in the reciprocating movements and engaging with the indicator, substantially as set forth. 100

12. The combination of a breech-bolt having a firing-pin recess and an indicator-recess 105 communicating with the firing-pin recess, an indicator projecting into the firing-pin recess, a firing-pin or hammer located in, and reciprocally movable in its recess at the intercommunicating opening between said two 110 recesses and not leaving it in either direction and engaging with the indicator, and means for operating the firing-pin or hammer, substantially as set forth.

In witness whereof I have affixed my signature in presence of two witnesses.

ARTHUR W. SAVAGE.
